Primary Examiner — S. Bryan Reinholdt, Jr.*Assistant Examiner* — Kaitlan Walker(74) *Attorney, Agent, or Firm* — NKL Law; Allen Xue(57) **CLAIM**

I claim the ornamental design for a scope reticle, as shown and described.

DESCRIPTION

The sole FIGURE is a front view of a scope reticle, showing my new design.

The dash-dash broken lines in the drawing show portions of the scope reticle which form no part of the claimed design.
